UNITED STATES PATENT OFFICE.

AARON LEVAUR, OF PHILADELPHIA, PENNSYLVANIA.

DESIGN FOR A PAPER OR DRAPING WEIGHT.

SPECIFICATION forming part of Design No. 36,039, dated September 2, 1902.

Application filed July 11, 1902. Serial No. 115,247. Term of patent 14 years.

To all whom it may concern:

Be it known that I, AARON LEVAUR, a citizen of the United States, residing at Philadelphia, county of Philadelphia, and State of Pennsylvania, have invented and produced a new, original, and ornamental Design for a Paper or Draping Weight, of which the following is a full, clear, and exact description, reference being had to the accompanying drawing, which forms a part of this specification.

The drawing shows a perspective view of a paper or draping weight, exhibiting my design.

The leading or material feature of my design consists of a paper or draping weight having an overhanging upper part or bust portion merging into and supporting a plurality of heads.

A is the base; B, the pedestal, which pro-

gressively narrows in an upward direction and is provided with a central bead b.

C is the overhanging part or bust portion, supported by the pedestal and which in turn supports and merges into a plurality of heads 25 D D' D², representing McKinley, Lincoln, and Garfield, respectively.

Having now described my invention, what I claim, and desire to secure by Letters Patent, is—

The ornamental design for a paper or draping weight, as herein shown and described.

In testimony of which invention I have hereunto set my hand, at Philadelphia, on this 2d day of July, 1902.

AARON LEVAUR.
